UNITED STATES PATENT OFFICE.

JOSEPH TESSIER AND ZOEL SEVIGNY, OF NEW BEDFORD, MASSACHUSETTS.

AUTOMATIC FIRE-EXTINGUISHER.

SPECIFICATION forming part of Letters Patent No. 680,084, dated August 6, 1901.

Application filed December 3, 1900. Serial No. 38,598. (No model.)

To all whom it may concern:

Be it known that we, JOSEPH TESSIER and ZOEL SEVIGNY, citizens of the United States, and residents of New Bedford, in the county 5 of Bristol and State of Massachusetts, have invented certain new and useful Improvements in Automatic Fire-Extinguishers, of which the following is a specification.

Our invention relates to that class of extinguishers which are usually secured to the 10 ceilings of rooms in mills and factories; and the object of our invention is to provide such a fire-extinguisher which shall be safe from being accidentally put in operation and which 15 shall be adjustable, so that when in operation to extinguish a fire the water from it may be made to cover a large or small floor-space.

To this end our invention consists in providing a shell for such automatic fire-extinguisher within which all its operating parts 20 are inclosed in such a manner that they are not liable to become displaced by any means except the heat from a fire; and it further consists in providing a distributer which may 25 be adjusted within the shell of the extinguisher so as to cause the water from the same to spread over a large or small floor-space.

The accompanying drawings illustrate our 30 invention, in which—
Figure 1 is a side elevation of our improved automatic fire-extinguisher as it appears when adjusted for use. Fig. 2 is a view of the same, showing one side broken away so as to expose its internal arrangements. Fig. 3 is a top 35 view of the distributer, and Fig. 4 is a view in vertical cross-section of the same through the dotted line $x-x$. Fig. 5 is a vertical section of the bottom part of the extinguisher, showing the manner of locking the arm with- 40 in the shell.

Similar letters refer to like parts in the several views.

The letter a represents the shell of our improved automatic fire-extinguisher, having a 45 water-passage a' through its center and provided with the ears h on opposite sides of its lower edge, between which are pivoted, respectively, the flat arms f and g .

The letter c represents the distributer, 50 which is supported in the shell a by and vertically movable on the screws m , which pass loosely through the apertures s and are

seated in the body of the shell a at v . The apertures s are counterbored at their lower ends in order that the screws m may not project below the rim of the shell when the distributer c is at its lowest position. The outer edge of the distributer is turned upward and provided with the notches d , which divides and distributes the water over a large space 60 when the water flows through the aperture a' . The arm g is provided with the lip p and the arm f with the notch q , as shown in dotted lines, Fig. 1. The upper surface of the distributer is provided with a suitable packing o in order that when the distributer c is pressed up against the lower end b of the aperture a' it will make a water-tight joint. The distributor c is held up against the end b of the aperture a' so as to form a water-tight joint 70 by the arms g and f pressing against its under side. The arm f is first folded up and then the arm g , whose lip p catches over the notched end q of the arm f , and the arms are then soldered together with metal which fuses 75 at a low temperature.

The operation of the device is as follows: The device being attached to a water-pipe at the ceiling of a room and a fire occurring in the room, the heat from the fire rises to the 80 ceiling of the room and fuses the solder on the arms f and g and allows them to swing downward and outward on their pivots and the distributer c to drop downward, as shown in Fig. 1, until the bottom of the counterbores 85 r rest on the heads of the screws m , thus opening the water-passage a' and exposing the notches d in the distributer below the rim of the shell a , and the water rushing through the said notches is divided and distributed 90 over a large floor-space to extinguish the fire. When it is desired that the water shall cover a less space, the screws m are adjusted so that the distributer shall drop to a lower point, thus allowing the water freer egress 95 and causing it to spread to a less extent. When the fire is extinguished, it is only necessary to fold up the arms to the position shown in Fig. 2 and resolder them together to put the device again in readiness for use, 100 none of the parts needing to be replaced with others.

All the operating parts of the device being contained within the shell a , it is not liable

to be opened accidentally by objects moved about the room, such as ladders, belt-shifters, &c.

Having thus described our invention, what we claim, and desire to secure by Letters Patent, is—

An automatic fire-extinguisher comprising a cylindrical shell having a central water-passage therethrough and an annular depending flange formed in the upper portion thereof, a distributor-plate loosely mounted upon screws adjustable within the shell, a packing-plate upon the upper face of the distributor, oppositely-arranged slots formed in the rim 15 of the shell, arms pivoted within the said

slots, one of said arms being formed with a recess *q* and the other with a lug *p*, adapted to engage the said recess, said arms being adapted to fold up within the shell, whereby accidental dislodgment is prevented, said arms being soldered together to hold the distributor against the annular depending flange to make a water-tight joint. 20
